UNITED STATES PATENT OFFICE.

HERBERT S. HUMPHREY, OF KALAMAZOO, MICHIGAN.

COMBINATION GAS AND WATER VALVE.

No. 890,057.

Specification of Letters Patent.

Patented June 9, 1908.

Application filed July 10, 1906. Serial No. 325,524.

To all whom it may concern:

Be it known that I, HERBERT S. HUMPHREY, a citizen of the United States, residing at Kalamazoo, county of Kalamazoo, 5 State of Michigan, have invented certain new and useful Improvements in Combination Gas and Water Valves, of which the following is a specification.

This invention relates to improvements in 10 valves.

It relates particularly to improvements in automatic water and gas valves for water heaters, although it is adapted for use in other relations.

15 The objects of this invention are: First, to provide an improved valve for water heaters, which compels the incoming or supply water to pass through the heater, and also permits the water in the system to circulate or pass through the heater when the supply valve is closed. Second, to provide an improved automatic water and gas valve in which the quantity of gas delivered is controlled by the quantity of the water delivered, 20 which may be readily adjusted. Third, to provide in a valve an improved means for adjusting the delivery port of the valve. Fourth, to provide an improved combination automatic water and gas valve for 25 water heaters, which is simple and economical in structure and convenient in use, and one which is not likely to get out of repair in use.

Further objects, and objects relating to 30 structural details will definitely appear from the detailed description to follow.

I accomplish the objects of my invention by the devices and means described in the following specification.

40 The invention is clearly defined and pointed out in the claims.

A structure embodying the features of my invention is clearly illustrated in the accompanying drawing forming a part of this 45 specification, in which,

Figure 1 is a detail elevation of a structure embodying the features of my invention, portions of the water heater casing being broken away to show the relation of the parts, and 50 details only of the circulating system being shown. Fig. 2 is a detail vertical section, taken on a line corresponding to line 2-2 of Fig. 1, showing the structural details of the valves. Fig. 3 is a detail transverse section, 55 taken on a line corresponding to the broken

line 3-3 of Fig. 2. Fig. 4 is an enlarged perspective of the adjustable member for controlling the port or passage of the inlet valve.

In the drawing, the sectional views are taken looking in the direction of the little 60 arrows at the ends of the section lines, and similar numerals of reference refer to similar parts throughout the several views.

Referring to the drawing, the casing 1 of the water heater may be of any desired construction, the structure illustrated being a double wall. Within this casing is the water heating coil 2, below which the burners, as 3, are arranged. The water heater is provided with a suitable flue, as 4, for the discharge of 70 the gases of combustion. The discharge pipe 5 of the water heater leads to the circulation system, which is here illustrated in conventional form only. The water supply pipe 6 is connected to the inlet pipe 7 of the heating 75 coils. The gas supply pipe 8 is connected by the pipe 9 to the burner. The circulation tank 10 is connected by the return pipe 11 to the inlet pipe 7 of the heating coils. The water inlet pipe, the circulation pipe, and the 80 gas supply pipe are controlled by an automatic water and gas valve, the details of which are illustrated in Figs. 2 to 4, inclusive. This valve comprises a casing 12, provided with an inlet passage 13, a circulation passage 85 14, and an outlet or discharge passage 15. The inlet passage 13 is connected to the water supply pipe 3, and the circulation passage 14 is connected to the return pipe 11 of the circulation system, while the discharge 90 passage 15 is connected to the inlet pipe 7 of the heater.

For convenience in referring to the parts, I herein designate the passage 14 as the circulation passage, and the valve 17, which controls this passage, the circulation valve. The valve casing 12 is provided with a chamber for the main or inlet valve 16, into which the inlet passage 13 opens; and also with a chamber into which the circulation passage 100 14 opens for the circulation valve 17. The inlet valve 16 is a piston valve, and preferably carries the circulation valve 17, which is preferably formed integral therewith, as is illustrated in the accompanying drawing. 105

The valve 17 in the structure illustrated is cylindrical in form, with notch-like ports in its lower end, which parts are open when the inlet valve is in its upper or closed position, and closed when the inlet valve 110

is opened; so that, when the inlet valve is closed, a circulation of water through the heater and the circulation system is permitted. The discharge port for the inlet valve is formed in one side of the main valve chamber, and is preferably provided so that the delivery of water is increased as the valve is opened. This I preferably accomplish by tapping a hole or chamber 18 into the valve casing, so that one side of the same opens into the inlet valve chamber. In this chamber 18, I arrange the block 19 which is supported adjustably therein by means of the stem 20, which is threaded into the block. The block 19 is tapered or inclined on its inner face, as at 21, so that, as the valve 16 curves downwardly, the area of the port is increased. The block 19 is preferably cylindrical in general form, and is prevented from turning by the pin 22, which projects into the hole 23 in the block. The stem 20 is provided with a suitable packing, consisting preferably of the ring 24, which is arranged against the collar 25 of the stem. A block-like gland 26 is threaded into the casing. Between the ring 24 and the gland 26 is a packing 27. These parts are all arranged in the plug 28, threaded into the casing, which is large enough to permit the insertion and removal of the block 19 therethrough.

The valves 16 and 17 are so arranged that the valve 17 is always closed when the valve 16 is opened, so that, when the valve 16 is opened, the water is compelled to pass to the heater, instead of circulating back through the circulation system. The valve is designed to be automatically operated by the water pressure, so that, when the water is turned on or the pressure in the system falls below that in the supply,—as is occasioned by the drawing off of water from the system—the valve 16 is automatically opened; and, when the pressure is equalized,—as by the closing of a faucet,—the valve 16 is again closed. A spring 29 is provided for this purpose. This spring is preferably arranged under the piston valve 16, within the circulation valve 17 and the chamber, as illustrated. When the inlet valve is closed, the circulation valve is opened, so that the water in the system is free to circulate through the heater. The valve 16 is provided with a stop 30, which is held normally against the top of the valve casing by the spring. The gas valve casing 31 is connected to the casing 12 by a suitable yoke, as 32. The gas valve casing is provided with an inlet passage 33, to which the supply pipe 8 is connected, and with a discharge passage 34, to which the burner pipe 9 is connected.

The delivery of the gas is controlled by the valve 35. The structure and arrangement of the gas valve is preferably that illustrated and described in my Letters Patent dated

May 30, 1905, No. 791,028, and I do not therefore describe the same in detail herein. The gas valve 35 is held normally in its seat by the spring 36. The stem 37 of the gas valve projects upwardly, and is engaged by the downwardly-projecting stem 38 of the water inlet valve. When the water inlet valve is opened, it, through the valve stem described, opens the gas valve. This gas valve is preferably of such structure that the quantity of gas admitted thereby is in proportion to the amount of water passing through the main water valve, as is pointed out in my patent above referred to. The valves in the accompanying drawing are shown in their closed positions. The arrangement of the pilot light valve is also preferably that illustrated in my patent referred to, the pilot burner 39 being connected by the pipe 40 to the valve casing.

By arranging the parts as I have illustrated and described, the passage of the water is effectively controlled, the valve being automatic in its operation in controlling both the delivery of the water and the gas, and permitting the circulation of the water in the system through the heater when the inlet valve is closed, and compelling the circulation of the fresh or incoming water to the heater when the inlet valve is opened. The structure is compact and simple, and not likely to get out of repair.

Having thus described my invention, what I claim as new and desire to secure by Letters Patent is:

1. The combination of a valve casing having a supply passage, a circulation passage, and an outlet passage, said casing also having an inlet valve chamber and a circulation valve chamber therein, and a port opening into said inlet valve chamber at one side thereof; a piston inlet valve; a cylindrical circulation valve carried by said piston valve; a block having an inclined inner face arranged in said port; a stem threaded into said block whereby the same may be adjusted to adjust the inlet valve port; a gas valve; and connections for said gas valve to said inlet valve, whereby said gas valve is controlled by said inlet valve, for the purpose specified.

2. The combination of a valve casing having a supply passage, a circulation passage, and an outlet passage, said casing also having an inlet valve chamber and a circulation valve chamber therein, and a port opening into said inlet valve chamber at one side thereof; a piston inlet valve; a cylindrical circulation valve carried by said piston valve; a block having an inclined inner face arranged in said port; means for adjusting said block; a gas valve; and connections for said gas valve to said inlet valve, whereby said gas valve is controlled by said inlet valve, for the purpose specified.

3. The combination of a valve casing having a supply passage, a circulation passage, and an outlet passage, said casing also having an inlet valve chamber and a circulation valve chamber therein, and a port opening into said inlet valve chamber at one side thereof; a piston inlet valve; a cylindrical circulation valve carried by said piston valve; a block having an inclined inner face arranged in said port; a stem threaded into said block whereby the same may be adjusted to adjust the inlet valve port, for the purpose specified.
4. The combination of a valve casing having a supply passage, a circulation passage, and an outlet passage, said casing also having an inlet valve chamber and a circulation valve chamber therein, and a port opening into said inlet valve chamber at one side thereof; a piston inlet valve; a cylindrical circulation valve carried by said piston valve; a block having an inclined inner face arranged in said port; means for adjusting said block, for the purpose specified.
5. The combination of a valve casing having a supply passage, a circulation passage, and an outlet passage, said casing also having an inlet valve chamber and a circulation valve chamber therein; a piston inlet valve; a cylindrical circulation valve carried by said piston valve; a gas valve; and connections for said gas valve to said inlet valve, whereby said gas valve is controlled by said inlet valve, for the purpose specified.
6. The combination of a valve casing having a supply passage, a circulation passage, and an outlet passage; a piston inlet valve; a circulation valve carried by said piston valve; means for adjusting the port of said inlet valve; a gas valve; and connections for said gas valve to said inlet valve, whereby said gas valve is controlled by said inlet valve, for the purpose specified.
7. The combination of a valve casing having a supply passage, a circulation passage, and an outlet passage; a piston inlet valve; a circulation valve carried by said piston valve; a gas valve; and connections for said gas valve, whereby said gas valve is controlled by said inlet valve, for the purpose specified.
8. The combination of a valve casing having a supply passage, a circulation passage, and an outlet passage; a piston inlet valve; a circulation valve carried by said piston valve; means for adjusting the port of said inlet valve, for the purpose specified.
9. The combination of a valve casing having a valve chamber and a port chamber opening into said valve chamber at one side thereof; a valve; a block having an inclined inner face arranged in said port chamber; and a stem threaded into said block whereby the same may be adjusted to adjust the valve port, for the purpose specified.
10. The combination of a valve casing having a valve chamber and a port chamber opening into said valve chamber at one side thereof; a valve; a block having an inclined inner face arranged in said port chamber; and means for adjusting said block, for the purpose specified.
11. The combination with a water heater, of a gas burner therefor; a circulation system connected to said heater; an automatic inlet valve; a circulation valve controlled thereby; means for adjusting the port of said inlet valve; a gas valve for controlling said burner; and connections for said gas valve to said inlet valve, whereby said gas valve is controlled by said inlet valve, for the purpose specified.
12. The combination with a water heater, of a gas burner therefor; a circulation system connected to said heater; an automatic inlet valve; a circulation valve controlled thereby; a gas valve for controlling said burner; and connections for said gas valve to said inlet valve whereby said gas valve is controlled by said inlet valve, for the purpose specified.

In witness whereof, I have hereunto set my hand and seal in the presence of two witnesses.
